FUSIBLE DOOR HOLDER

Earl L. Heverly, Chicago, Ill., assignor to The
Yale & Towne Manufacturing Company, Stamford,
Conn., a corporation of Connecticut

Application February 3, 1934, Serial No. 709,606

12 Claims. (Cl. 189—49)

This invention relates to a holding device for doors, and more particularly to a holding device adapted for use in combination with a door closer, and adapted to be released by means 5 fusible when exposed to heat.

More particularly, it is the object of my invention to provide a holding device for a fire door closer assembly, wherein the usual pair of arms of the assembly carry a pair of discs piv- 10 otally rotatable relatively to one another, and adapted to be rotated to a position wherein the discs will jam frictionally against each other and against a spacer member, which in turn, is held in operative position by a fusible link element. 15 The operation of the device is such that when the fusible link gives way under heat, the spacer member will be withdrawn from operative position, and the frictional engagement between the discs will be relieved so that the door closer of 20 which the arms form a part, will move the door to a closed position.

I appreciate that the art of fusible link closer arms has been very highly developed. However, the holding device constituting my invention, is 25 adapted to allow for a very positive and quick release which is extremely desirable in the art. While, therefore, my invention is in a relatively narrow field when considered in view of the prior art, it is nevertheless of considerable importance 30 in that field, and it is my intention to claim rather broadly the particular combination I will disclose below.

More in detail, my invention comprises, in one of its modifications, a pair of arms having at 35 their ends holding discs. One of the discs is screw threaded relatively to a shaft while the other disc is slidably mounted on this same shaft, but is non-rotatable relatively thereto. At the end of the shaft there is a limiting nut and between this limiting nut and one of the discs, there are a pair of lever spacing members which 40 are pivoted to one of the discs and which are adapted to occupy a position between the discs and the limiting nut member. Because of the screw threaded relation of one of the discs to 45 the stud, it is obvious that rotation of the arms relatively to one another, will force the two discs together and against the spacing members and solidly against the end limiting nut. In this relation of the parts there will be a binding or 50 jamming relation of the various surfaces so that the holder arms will be held in a position in which the door will be maintained open.

It is a further feature of my invention, that 55 cam means are provided preferably between the

end limiting nut and the lever spacing members, although such cam means may be present elsewhere, or may be eliminated in favor of spring devices or other means, these cam means acting to force the lever spacing members laterally out of binding relation to the elements on the said shaft. For preventing the two lever members from flying out of binding relation, I utilize a fusible link in combination with a series of levers which are arranged to overcome the considerable 10 force tending to move the spacing members out of binding relation. However, should the fusible link give way as under heat, the spacing members will be adapted to move laterally and will release the binding engagement between the two 15 discs of the closer arms, and the door closer will be allowed to move the door to a fully closed position.

I also apply my invention to a further door holding combination in which the discs of the 20 two door closer arms are arranged in pivotal relation rather than in screw-threaded relation to one another, the two discs having cam surfaces whereby they may bind relatively to one another and the spacing levers and end limiting device 25 on a pivotal shaft, as the closer arms rotate relatively to each other on the shaft.

For a detailed description of my invention I shall now refer to the drawings, wherein Fig. 1 illustrates a door and closer assembly to which 30 my invention is applied. Fig. 2 is a top view of the pivotal door holding assembly of my invention while Fig. 3 is a cross section along lines 3—3 of Fig. 2. Fig. 4 is a side view of the parts of Fig. 2 showing the discs and lever spacing 35 members in binding relation to the end limiting nut. Fig. 5 is a view similar to Fig. 2 showing the relation of the parts when the fusible link gives way. Fig. 6 is a further view of the parts of Fig. 5 showing the relation of the various 40 parts after the holding relation of the arms, discs and lever spacing members has been released so that the door closer arms may move into a closed position. Fig. 7 is a side view of the parts of Fig. 6 but showing the discs modified 45 for operation with a plain shaft having limiting means on both ends, and where the binding action is accomplished by the binding of the cam surfaces of the discs.

Referring now more particularly to the drawings and especially Fig. 1, reference numeral 10 indicates a door closer of the usual type in which a spring is adapted to rotate a central shaft 11 in a direction so that the door 12 on which the closer 10 is applied, will be actuated into a closed 55

position by cooperation of the arm 13 secured to the shaft 11 with the arm 14 secured to the frame 15 of the door.

The closer arm 13 has at one end a disc 16 slidably but not rotatably mounted on the square portion 17 of a stud shaft 18. The door closer arm 14 has secured thereto a disc 19 which is screw threaded on the stud shaft 18 and in such a manner that relative rotation of the arms 13 and 14 will tend to move the disc 19 into frictional engagement with the disc 16 as will be quite apparent.

There is provided a nut 20 threaded onto the stud shaft 18 which functions as an end limiting device against which the rotation of the disc 19 on the screw threads forces the disc 16, so that there may be a binding action between the nut 20, the disc 16, and the disc 19, where only a simple door holding action is required. However, since in the present invention, it is required that a fusible releasing mechanism be provided, further means in the form of the lever spacing members 21 are provided.

These lever members are best illustrated in Figs. 2, 5, and 6 and are shown as pivoted at points 22 on the upper disc 16. Each lever spacing member 21 is equipped with a cam surface 23, this cam surface cooperating with the under face of the nut 20 so that when the two arms 13 and 14 are moved into the position illustrated in Fig. 2, and also in Fig. 3, there will be a binding between the discs 16, 19, the lever spacing member 21, and the end limiting nut 20, this binding or jamming relation of the parts being sufficient to overcome the action of the spring of the closer 10 so as to maintain the door 12 in an open position.

It will be quite obvious that when the parts are jammed together there will be considerable force exerted between the end limiting nut 20 and the lever spacing members 21 through the intermediary of the cam surfaces 23 of the lever members. Incidentally, while I have provided cam surfaces on both the end limiting nut 20 and the lever spacing members 21, it should be understood that the cam surfaces may be located between the discs and the lever members or between any of the other parts in the assembly, or that even other means, such as springs tending normally to urge the lever spacing members out of spacing position may be provided.

In order to overcome the considerable force of the cam surfaces tending to move the lever spacing members 21 in a horizontal direction out of their jamming relationship to the several devices mounted on the stud shaft 18, I utilize a lever member 24 pivoted at 25 to one of the lever members 21, and carrying a further lever 26 pivoted at 27 thereto. This auxiliary lever 26 cooperates with a pin 28 on the lever member 21 for holding the two spacing members 21 in the position of Fig. 2 in which they are in a position wherein they will bind with the discs 16 and 19 against nut 20 to hold the door in open position.

There is provided a springy rod member 29 pivoted at 30 to the lever member 21 which maintains the auxiliary lever 26 in holding relationship relatively to the pivot or stud 28. This rod member 29 is in turn held in its holding position by a fusible link member 31 cooperating at its other end with the first mentioned lever 24. It is necessary to use this rather unusual system of levers in order that the relatively weak fusible link 31 will be enabled to maintain the two spacing members 21 in binding position against the

force exerted on the cam surfaces 23, this force being very considerable. If the fusible link member 31 were used directly to overcome the force exerted against the cam surfaces 23, it would have to be of such heavy construction that it would lose its sensitivity.

It is quite easily seen that should heat be applied to the fusible link 31, it will give way, allowing the lever members 24 and 29 to swing as illustrated in Figs. 5 and 6, releasing the lever 10 spacing members 21 as illustrated in Fig. 6, and withdrawing them from the binding engagement shown in Fig. 3, so that the entire binding or jamming relation of the parts of Fig. 3 will be relieved and the parts allowed to move in the 15 direction illustrated in Fig. 6, wherein the closer arms 13 and 14 are shown already moved into a more fully closed relation than in Fig. 5.

Fig. 7 is a composite figure illustrating the release of the binding relation in Fig. 6 between the lever spacing members 21 and the end limiting nut 20. It also illustrates a pair of discs which bind due to their cam relation rather than due to a screw threaded relation similar to that of Fig. 3. It is quite easily seen that the surfaces 25 of the discs 16 and 19 in Fig. 7 are such that relative rotation will act to bind the two together against the bottom limiting nut 32 and the upper limiting nut 20.

It will be of interest also to note that in Fig. 4, 30 I show the upper and lower discs slightly tapered rather than at direct right angles to their axis of rotation. This is done so that the binding will be on merely part of the surfaces of the discs rather than on their entire surfaces, thus giving 35 a more resilient binding action. The binding action first takes place on a part of the surfaces of the two discs, and then upon further forceful opening of the door, will take place on more of the surfaces of the two discs than shown in Fig. 4. 40 This gives a very desirable commercial result.

I now claim:

1. A door holding device comprising a pair of arms, a pivotal mounting for said arms, additional means in said pivotal mounting so arranged 45 relatively to said arms that predetermined relative pivotal movement of said arms will act to jam said means and arms about said pivotal mounting so as to maintain them in a door holding position, a lever constituting one of the elements of said additional means and itself held in said frictional jam, means under the influence of the jamming action tending to force said lever laterally out of its jammed position whereby to effect the release of the arms on the mounting, 55 and a fusible link adapted to maintain said lever in its jammed position against the force of said second named means.

2. A door holding device comprising a pair of arms, a pivotal mounting for said arms, additional means in said pivotal mounting so arranged 60 relatively to said arms that relative pivotal movement of said arms will act to jam said means and arms about said pivotal mounting so as to maintain them in a door holding position, 65 a lever constituting one of the elements of said additional means and itself held in said frictional jam, a cam surface on said lever cooperable with a second cam surface on one of the elements in said jamming frictional assembly, said cam surfaces being arranged so that said lever is continually urged out of its jammed position, and a fusible link adapted to maintain said lever in its jammed position against the action of said cams.

3. A door holding device comprising a pair of 75

- arms and a shaft whereby the arms may move pivotally relatively to one another as the door moves to and from its closed position, additional means associated with said shaft and arranged to 5 jam frictionally with portions of said arms when said arms have moved to a predetermined position corresponding to an open position of the door, whereby to maintain the door in said open position, a member forming one of the additional 10 means in the frictional jam and itself held frictionally in said jam, means whereby the jamming action tends to move said member out of jammed position, and a fusible element adapted to hold said member in said jammed position.
- 15 4. A door holding device comprising a pair of arms and a shaft whereby the arms may move pivotally relatively to one another as the door moves to and from its closed position, additional means associated with said shaft and arranged to 20 jam frictionally with portions of said arms when said arms have moved to a predetermined position corresponding to an open position of the door, whereby to maintain the door in said open position, a member forming one of the means in the frictional jam on said shaft and itself held frictionally in said jam, a cam surface forming one of the surfaces of said member cooperating with the other means in said jam and acting to cam said member out of its jammed position, 25 and a fusible link adapted to hold said member in its jammed position against the action of said cam surface.
5. A door holding device comprising a pair of arms and a shaft whereby the arms may move pivotally relatively to one another as the door moves to and from its closed position, additional means associated with said shaft and arranged to 30 jam frictionally with portions of said arms when said arms have moved to a predetermined position corresponding to an open position of the door, whereby to maintain the door in said open position, a pair of members forming part of said frictional jam and themselves held frictionally in said jam, a cam surface on each of said members cooperating with surfaces of the other elements in said jam and acting to cam said members out of their jammed position, and a fusible link adapted to hold said members in their 35 jammed position against the action of said cam surfaces.
6. A door holding device comprising a pair of arms, a stud shaft forming a part about which said arms may rotate relatively to one another, a limit device on said shaft, and a member acting as a spacer element on said shaft but mounted so as to move laterally relatively to said shaft, said arms and spacer member being adapted to 40 jam against said limit device as said arms rotate relatively to each other in moving to a predetermined position, said spacer member being operable to loosen said jam if moved laterally relatively to said shaft, and a fusible link adapted to maintain said lever against such lateral movement.
- 45 7. A door holding device comprising a pair of arms, a stud shaft forming a pivot about which said arms may rotate relatively to one another, a limit device on said shaft, and a member acting as a spacer element on said shaft but mounted so as to move laterally relatively to said shaft, said arms and spacer member being adapted to 50 jam against said limit device as said arms rotate relatively to each other in moving to a predetermined position, said spacer member being operable to loosen said jam if moved laterally.

relatively to said shaft, a cam surface on said member cooperable with another surface on the pivotal assembly and exerting a pressure on said member tending continuously to move it laterally relatively to said shaft, and a fusible link adapted to maintain said member against lateral movement. 5

8. A door holder comprising a pair of arms having holding portions in the form of disc surfaces pivotally mounted about a shaft, a limit device on said shaft, a spacer member on said shaft and mounted so as to move laterally relatively thereto, said disc surfaces being in the form of inclined cams whereby when they rotate relatively to one another, they jam one another and the 15 spacer member against said limit device and into a firm holding relationship, a cam surface on said spacer element tending to cam it laterally out of jammed relation to said discs and shaft limit device whereby to release said arms from said holding relationship, and a fusible link adapted to maintain the spacer member in its position against the force of said cam. 20

9. A door holder comprising a pair of arms having holding portions in the form of disc surfaces 25 pivotally mounted about a shaft, a limit device on said shaft, a spacer member on said shaft and mounted so as to move laterally relatively thereto, said disc surfaces being in the form of inclined cams whereby when they rotate relatively to one 30 another, they jam one another and the spacer member against said limit device and into a firm holding relationship, means tending continuously to force said spacer member laterally and out of jammed relation to said discs and shaft limit device whereby to release said arms from said holding relationship, and a fusible link adapted to maintain the spacer member in its position against the force of said means. 35

10. A door holder comprising a pair of arms 40 having holding portions comprising disc surfaces pivotally connected through the intermediary of a shaft, a limit device on said shaft, a pair of spacer members pivoted on one of said arms and adapted to act as spacers on said shaft and to lie 45 between said limit device and said disc surfaces, said spacer members being pivotally movable laterally out of said position whereby to leave a space on said shaft, said disc surfaces being in the form of inclined cams whereby when they rotate relatively to one another on the shaft they jam one another and the spacer members against the shaft limit device and into a firm holding position, means tending continuously to force said spacer members laterally on their pivots out of jammed 50 relation to said discs and shaft whereby to release said arms from said holding relationship, and a leverage system connecting said spacer members through the intermediary of a fusible link and functioning to maintain the members in their 55 jammed position against the force of said means. 60

11. A door holder comprising a pair of arms having holding portions in the form of disc surfaces, a stud shaft upon which one of said discs is screw threaded, and upon which the other disc 65 is slidable, a limit device on said shaft, a spacer member on said shaft and mounted so as to move laterally relatively thereto, said discs when rotated relatively to one another being adapted to jam one another and the spacer member against said limit device and into a firm holding relationship, cam means tending to cam said spacer member laterally out of jammed relation to said discs and shaft limit device whereby to release said arms from said holding relationship, and a fusible link adapt- 70 75

ed to maintain the spacer member in its operative position against the force of said cam means.

12. A door holder comprising a pair of arms having holding portions in the form of disc surfaces, a stud shaft upon which one of said discs is screw threaded, and upon which the other disc is slideable but not rotatable, a limit device on said shaft, a pair of spacer members pivoted on one of said arms and adapted to act as spacers on said shaft and to lie between said limit device and said disc surfaces, said discs when rotated relatively to one another being adapted to jam one

another and the spacer members against said limit device and into a firm holding position, means tending continuously when said elements are jammed together to force said spacer members laterally on their pivots out of jammed relation to said discs and shaft whereby to release said members from holding relationship, and a leverage system connecting said members through the intermediary of a fusible link and functioning to maintain the spacer members in their jammed position against the force of said means. 5

EARL L. HEVERLY.
